UNITED STATES PATENT OFFICE.

EDMUND C. TREESE, OF HUNTINGTON, WEST VIRGINIA, ASSIGNOR TO SULLIVAN MACHINERY COMPANY, A CORPORATION OF MASSACHUSETTS.

MINING MACHINE.

Application filed October 12, 1921. Serial No. 507,844.

To all whom it may concern:

Be it known that I, EDMUND C. TREESE, a citizen of the United States, residing at Huntington, in the county of Cabell and State of West Virginia, have invented certain new and useful Improvements in Mining Machines, of which the following is a full, clear, and exact specification.

My invention relates to mining machines. It has for its object to provide an improved feeding mechanism especially adapted for use with mining machines of the room and pillar type. A further object of my invention is to provide an improved sumping mechanism whereby a machine utilizing a guide relative to which the machine moves during sumping, as for instance a cutter chain guard, may be conveniently and expeditiously summed into the work. These and other objects and advantages of my improved construction will, however, herein-after more fully appear.

In the accompanying drawings I have shown for purposes of illustration two forms which my invention may assume in practice.

In these drawings,—

Fig. 1 is a plan view of my invention applied to a mining machine utilizing a cutter chain guard, the machine being of the chain propelled type.

Fig. 2 is a side elevation of the rear end of the construction shown in Fig. 1.

Fig. 3 is a plan view of my invention applied to a similar machine utilizing a cutter chain guard, the machine however being of the cable fed type.

Referring first to the illustrative construction shown in Figs. 1 and 2, a mining machine is there shown comprising a motor casing 1 and cutter bar 2 projecting therefrom, the bar carrying a cutter chain 3 equipped with cutter bits 4, and the casing carrying a feed operating member 5 having a cooperating flexible feeding member 6, herein in the form of a feed chain, which may be disposed relative to usual guide members 7 in such a manner as to feed the machine transversely of the face in a usual way. As in a usual construction the cutter chain and the feed operating member are both driven by a motor on the casing 1 through usual and well-known connections (not shown), and the feed operating member is, as herein, controlled by a friction

mechanism including a controlling member 8 and a reverse lever 9, the reverse lever being adapted to prevent operation of the friction lever 8 and to cause the rotation of the feed operating member 5 in one direction to produce a "slow feed" when the member 9 is in the full line position illustrated. As also in a well known construction, a chain guard is carried by the casing 1, herein of the telescopic type and adapted to telescope in the casing 1 and comprising the usual side members 10 at the side of the cutter chain and the usual cross bar 11 connecting the side members and having a shoe 12 adapted to slide on the mine bottom, the chain guard being as usual adapted to be held in extended position by suitable means as by a pin 13 and to be fixed to the bottom during sumping by suitable means as by a jack 14.

In my improved construction, I have provided a guiding member 15, herein in the form of the feed sprocket, rotatable on a transverse axis on the transverse member 11 and, specifically, herein rotatable on such an axis on a protruding end 16 of the member 11 extending closely adjacent the right hand rib, the jack 14 being mounted on a corresponding protruding end 17 on the opposite side of the bar. In my improved construction, one end of the flexible feeding member 6 is also carried from the feed operating member 5 around two of the rear guides 7 and to and around the guide 15 from which it is then carried back and fixed to the machine. Herein, the chain 6 is attached to the rear end of the machine, a suitable hook 18 being provided on the end of the chain to cooperate with a plurality of chain links 19 carried on a suitable eye 20 on the receding side of the rear end of the machine.

In the use of my improved construction, the machine is unloaded from its truck in the usual manner preferably with its cutter chain guard 10, 11 extended and held in extended position by suitable means as by the pin 13. When the machine is disposed adjacent the rib in position for sumping as shown in Fig. 1, the pin 13 is withdrawn and the chain guard 10, 11 is jacked down in position in the usual manner by the jack 14, while the flexible feeding member is extended forward and around the guide 15 in a double strand connection with its free end.

connected by the hook 18 to the chain links 19. The feed operating member 5 is then rotated, through a suitable movement of the reverse lever 9 in to its full line position, 5 in such a manner as to rotate the feed operating member 5 at its fast or reverse speed and by drawing in the flexible feeding member 6 thereby cause the machine to be moved bodily forward relative to the chain guard 10 and the guide member 15 at one-half its usual fast or reverse speed, although it will be understood that this speed may be varied by suitable adjustment of the friction mechanism including the lever 8. Obviously when the bar 2 has been sumped in under the coal, the chain guard 10, 11 will have telescoped into the casing 1 and through a suitable reconnection of the flexible feeding member to the right and left hand ribs, the machine may be straightened 20 in the cut and moved transversely in a usual manner.

In the form of my invention shown in Fig. 3, it will be noted that a machine 1 is shown having the same cutter bar 2, cutter chain 3, and bits 4, but adapted to be driven by two flexible feeding members 21 and 22 which are in turn driven by drums 23 and 24 in a well known manner, the drum 23 being the slow feed drum while the drum 24 is the fast feed drum. In this construction, as in my preceding construction, a chain guard 10, 11 is provided which is adapted to be jacked in position by a jack 14 and held in 25 extended position by a pin 13, the construction in that respect being identical with that heretofore described. Here, however, the guiding member carried by this chain guard is in the form of a horizontally disposed 30 guide sheave 25 rotatable on a vertical axis, and the cable 22 which extends around this guide sheave 25 is connected as through a hook and eye connection 26 to the front end of the machine casing 1, as I find this connection better adapted to use with a mechanism wherein the cable passes off of the under side of the drum, though obviously the arrangements of parts may be varied to 35 suit different constructions of this type.

While I have in this application specifically described two forms which my invention may assume in practice, it will be understood that these forms have been shown for 40 purposes of illustration and that the invention may be modified and embodied in various other forms without departing from its spirit or the scope of the appended claims.

What I claim as new and desire to secure 45 by Letters Patent is:

1. In a mining apparatus, a mining machine having a frame and telescopic guiding means supported by said frame adapted to be fixed in extended position, and a self-contained feeding means independent of the 50 fixation means having operative connection

with said guiding means and said machine frame.

2. In a mining apparatus, a mining machine having a frame and a telescopic cutter guard supported by said frame adapted to 70 be fixed in extended position, and a self-contained feeding means independent of the fixation means having operative connection with said cutter guard and said machine frame. 75

3. In a mining apparatus, a mining machine having a frame, a flexible feeding member and a cutter chain guard adapted to telescope within said frame, and means for disposing said flexible feeding member in 80 double strand sumping connection with said guard.

4. In a mining apparatus, a mining machine having a frame and a telescopic guiding member supported by said frame, a flexible feeding member, and means for disposing said feeding member in double strand sumping connection with said guiding member. 85

5. In a mining apparatus, a mining machine 90 slideable on its bottom on a mine bottom and having a frame, a flexible feeding member on the receding side thereof and a telescopic cutter chain guard supported by said frame, and means for disposing said flexible feeding member in sumping connection with said guard.

6. In a mining apparatus, a mining machine slideable on the mine bottom having a 100 frame and a flexible feeding member, a machine guiding member supported by said frame, and sumping means including a guiding member carried on said machine guiding member for disposing the flexible feeding member in a double strand connection. 105

7. In a mining apparatus, a mining machine slideable on the mine bottom having a frame and a flexible feeding member, a machine guiding member supported by said frame, and sumping means including a 110 rotatable guiding member carried on said machine guiding member for disposing the flexible feeding member in a double strand connection. 115

8. In a mining apparatus, a mining machine slideable on the mine bottom having a frame and a flexible feeding member and a cutter chain guard adapted to telescope within said frame, a guide member on said guard around which said feeding member extends in a double strand connection, and means for connecting the free end of said member to said machine. 120

9. In a mining apparatus, a mining machine 125 having a frame and a flexible feeding member and a telescopic cutter chain guard supported by said frame, and means for disposing said flexible feeding member in a double strand sumping connection includ- 130

ing a guiding member carried on said guard, and means for connecting the free end of said flexible member to said machine.

10. In a mining apparatus, a mining machine slideable on its bottom on a mine bottom and having a frame, a flexible feeding member on the receding side thereof and a telescopic cutter chain guard supported by said frame, and means for disposing said flexible feeding member in a double strand sumping connection including a guiding member carried on said guard.

11. In a mining apparatus, a mining machine slideable on its bottom on a mine bottom and having a frame, a flexible feeding member and a telescopic cutter chain guard supported by said frame, and means for disposing said flexible feeding member in a double strand sumping connection when said guard is fixed in extended position including a rotatable guiding member carried on said guard and disposed adjacent one side thereof.

12. In a mining apparatus, a mining machine slideable on its bottom on a mine bottom and having a frame, a flexible feeding member and a telescopic cutter chain guard supported by said frame, means for disposing said flexible feeding member in a double strand sumping connection when said guard is fixed in extended position including a rotatable guiding member carried on said guard and disposed adjacent one side thereof, and a jack acting on the opposite side of said guard.

13. In a mining apparatus, a mining machine including a frame slideable on its bottom on a mine bottom and having a flexible feeding member on the receding side thereof and a cutter chain guard adapted to telescope within said frame, and means for disposing said flexible feeding member in a double strand sumping connection including a guiding member carried on said guard.

14. In a mining apparatus, a mining machine slideable on its bottom on a mine bottom and having a frame, a flexible feeding member and a cutter chain guard adapted to telescope within said frame, and means for

disposing said flexible feeding member in a double strand sumping connection when said guard is fixed in extended position including a rotatable guiding member carried on said guard and disposed adjacent one side thereof.

15. In a mining apparatus, a mining machine slideable on its bottom on a mine bottom and having a frame, a flexible feeding member and a cutter chain guard adapted to telescope within said frame, means for disposing said flexible feeding member in a double strand sumping connection when said guard is fixed in extended position including a rotatable guiding member carried on said guard and disposed adjacent one side thereof, and a jack acting on the opposite side of said guard.

16. In a mining apparatus, a mining machine having a casing carrying feed operating mechanism, a flexible feeding member having advance and receding portions cooperating therewith, guiding means for said machine having telescopic relation with said casing, and means on said guiding means for connecting said receding portion to feed the machine longitudinally.

17. In a mining apparatus, a mining machine having a frame and telescopic guiding means supported by said frame provided with a transverse member, a flexible feeding member having operative connection with said transverse member, and means engaging said transverse member operative to hold the same in position and to cooperate with said flexible feeding member for longitudinally advancing said machine.

18. In a mining apparatus, a mining machine having a frame and a chain guard supported by said frame provided with a transverse member, a flexible feeding member having operative connection with said transverse member, and means engaging said transverse member operative to hold the same in position during longitudinal movement of said machine.

In testimony whereof I affix my signature.

EDMUND C. TREESE.
